To all whom it may concern:

Be it known that I, JOHN KORZINEK, a citizen of the United States, residing in the city of Passaic, in the county of Passaic and State of New Jersey, have invented a new, original, and ornamental Design for a Floral Border to be Applied to Wall-Paper; and I hereby declare the following to be a description of the same in such terms as will enable any one skilled in the art to which it appertains to make and use the same, reference being had to the accompanying drawing.

The figure of the drawing is a plan view illustrating my new design of wall paper border which configuration is intended to be repeated or matched out upon either side in-

definitely as is familiar to those skilled in this art.

The design is intended for use by printing the same on wall paper and comprises a central bunch of chrysanthemum flowers and leaves A, from each side of which extend sprays of leaves B. Above the bunch of chrysanthemum flowers is a border of leaves and buds C and an ornamental strip.

What I claim is:
